UNITED STATES PATENT OFFICE.

EDWARD C. PARAMORE, OF PHILADELPHIA, PENNSYLVANIA.

APPARATUS FOR TREATING CHLORIN GAS.

SPECIFICATION forming part of Letters Patent No. 667,100, dated January 29, 1901.

Application filed March 27, 1900. Renewed November 19, 1900. Serial No. 37,063. (No model.)

To all whom it may concern:

Be it known that I, EDWARD C. PARAMORE, a citizen of the United States, residing at Philadelphia, (Germantown,) in the county of 5 Philadelphia and State of Pennsylvania, have invented new and useful Improvements in Apparatus for Treating Chlorin Gas, of which the following is a specification.

My invention relates to apparatus for generating, treating, and utilizing chlorin gas; and the objects of the same are to provide an apparatus for this purpose which will thoroughly subject every molecule of the gas to the action of electric discharges in a chamber 15 from which the air has been expelled, and in this way to practically deodorize the gas and enhance its bleaching qualities.

In the accompanying drawings, forming part of this specification, and in which like 20 characters of reference indicate corresponding parts, I have illustrated two of the many forms of apparatus that may be employed in carrying my invention into effect, it being understood that I do not limit myself specifically 25 to these particular forms of apparatus, and in the drawings—

Figure 1 illustrates one form of apparatus which I may use. Fig. 2 is a detail view of one form of electric chamber in which the gas 30 is treated in the above-mentioned form of apparatus. Fig. 3 is a cross-section on line xx , Fig. 2. Fig. 4 is a cross-section on line yy , Fig. 2.

Referring to the drawings and to Fig. 1 thereof, A designates the electrolytic apparatus, the same comprising a four-armed structure, whereof two tubes or arms a a constitute a passage-way for the gas as generated and the other two arms a^2 a^2 the housing for 35 the electrodes B. The members a^2 , as shown, each consists of an inner and outer glass tube, the inner tube a^3 a^3 of each member being extended nearly to the center of the structure, whereby the electrodes will be brought sufficiently close together to permit passage of the 45 current between the two. The electrodes are in this instance shown as a plurality of wires, of iron or any suitable material, bunched or otherwise suitably arranged and connected 50 to a wire a^4 , common to all of the electrodes, this wire being extended outward beyond each member to permit of attachment with

the conducting-wires from the source of electricity. The numeral 1 designates a generator for the chlorin gas, and 2 a tube which 55 extends from the generator to the electric apparatus. The generator is supported by a stand 3. A spirit-lamp 4 may be placed under said generator, and a funnel 5 is connected to the inlet-pipe 6, provided with a stop-cock 7. 60

As shown in Fig. 1, the generator is connected to one of the tubes a , and the opposite tube a is connected at 8 to a receiver 9 for containing pulp or other material to be treated, all the joints in the apparatus being air and 65 gas tight. A pump 10, of any suitable construction, may be applied to pipe 11, leading from the receiver.

The electricity may be from any preferred source, in this instance from a Ruhmkorff 70 coil E, to which the terminals are suitably connected.

The generator 1 for the gas may be an ordinary retort, such as is commonly used, into which manganese dioxide and an aqueous solution of hydrochloric acid are introduced, as 75 usual.

In the form of apparatus shown the space between the inner and outer arms a^2 a^2 constitutes a trap into which any condensed acid 80 may accumulate in the operation of the device, thus preventing contamination of the purified gas.

The operation of the apparatus described is as follows: Manganese dioxide and an aqueous solution of hydrochloric acid are placed 85 in the generator, and the stop-cock 7 is then turned to exclude the air. The air is then expelled from all parts of the apparatus—viz., the receiver 9, the tubes a a^2 , and the generator 1. The lamp 4 may then be lighted and the gas will be generated. The pump is then 90 put into operation, and the gas is drawn through the electric chamber and through the material in the receiver 9. It is to be noted 95 that the space between the inner and outer tubes in the apparatus A is comparatively small, and as a result every molecule of gas receives treatment in a confined or restricted space, the electrodes, however, never coming 100 in direct contact with the gas, the sparks passing through the dielectric material of which the inner tubes are formed.

In Figs. 2, 3, and 4 I have shown a modified

form of electrolytic apparatus in which the electrodes instead of being bunched, as in Fig. 1, are separately inclosed in glass tubes and hermetically sealed. Any suitable number of electrodes may be used, and they may be arranged in various ways to perform their function. As shown at the bottom of Fig. 2 and in Fig. 4, the electrodes are in the form of spiral coils. The single wire α^4 may pass through a cork α , fitted in the top and bottom of the inner tube α^3 , and it is to be understood that this closure need not be air-tight, as shown in Fig. 1, as it does not admit air to the interior of the apparatus; but in Fig. 2 the closure must be hermetic, because in this construction the inner and outer tubes are not in one piece, as in Fig. 1.

I do not claim herein the process made the subject of my application, Serial No. 6,099, filed February 21, 1900.

Having thus fully described my invention, what I claim is—

1. In an apparatus for treating chlorin gas, an electric chamber consisting of a gasway-tube, housings extending at right angles to said tube, dielectric bulbs containing electrodes suspended in said housings, in combination with a chlorin-generator connected to said gasway-tube, a pump connected to a receiver, an induction-coil, and electrical connections between said induction-coil and electrodes.

2. In an apparatus for treating chlorin gas, an electric chamber consisting of a gasway-tube, housings extending at right angles to said tube, dielectric bulbs containing elec-

trodes, said bulbs extending through the housings and into the gasway-tube, in combination with a chlorin-generator and a receiver, both connected to said gasway-tube, a pump 40 connected to the receiver, an induction-coil, and electrical connections between said induction-coil and electrodes.

3. In an apparatus for treating chlorin gas, the combination of a chlorin-generator, a gas- 45 way-tube connected to said generator, a receiver also connected to said gasway-tube, dielectric bulbs containing electrodes, housings for said bulbs, said bulbs extending into the gasway-tube, an induction-coil electrically connected to said electrodes, and a pump 50 connected to said receiver, substantially as described.

4. In an apparatus for treating chlorin gas, the combination of a chlorin-generator, an 55 electric chamber, a receiver and a pump connected thereto, said electric chamber consisting of a gasway-tube connected at its ends to the generator and to the receiver, housings extending at right angles to the gasway-tube, 60 dielectric bulbs in the housings, electrodes in the bulbs, and an induction-coil electrically connected to the electrodes, the space between the bulbs and housings forming a trap for condensed acid, substantially as described. 65

In testimony whereof I have hereunto set my hand in presence of two subscribing witnesses.

EDWARD C. PARAMORE.
